FILLING MACHINE

John Bousquet, Copiague, N. Y., assignor to
 Beech-Nut Packing Company, Canajoharie,
 N. Y., a corporation of New York

Application January 12, 1946, Serial No. 640,849

2 Claims. (Cl. 226—2)

1

The present invention relates to machines for filling cartons or boxes, and particularly boxes for packaging candy-coated gum such as five cent boxes of "Beechie," and has for its object to provide a novel and improved machine of this character.

The several features of the invention, whereby this and other objects may be attained, will be readily understood from the following description and accompanying drawings, in which:

Figure 1 is a sectional plan view of a portion of a box-filling machine embodying the features of the invention in their preferred form, the section being taken substantially on line 1—1 of Fig. 3;

Fig. 2 is a sectional elevation, taken substantially on the line 2—2 of Fig. 1; and

Figs. 3 and 4 are sectional views taken respectively on lines 3—3 and 4—4 of Fig. 1.

The machine illustrated in the drawings is particularly adapted for use in packaging pieces of candy-coated gum 2, the pieces being in the form of rectangular tablets as customary.

The machine as shown comprises a plurality of open-ended trays 4 that are fed side by side on an endless conveyor (not shown), the trays during a portion of their travel sliding on horizontal rails 6. Each tray is adapted to receive twelve pieces or tablets 2 which are arranged in two rows extending transversely of the direction of travel of the trays. When the tablets are thus positioned in the trays, suitable mechanism (not shown) pushes the tablets out of one of the ends of each tray and into the box.

The trays are fed intermittently so as to position each tray successively at six stations. When each tray is at each station two tablets 2, positioned end to end, are fed sidewise into one of the ends of the tray, so that when the tray has passed the last of the six stations the tray is filled with the twelve tablets as described.

The means illustrated for thus feeding the tablets into the trays at each of said stations comprises two slotted wheels 8 which are intermittently rotated in opposite directions. Each wheel 8, is provided with four radial slots 10, and the wheels are thus rotated ninety degrees so as to position each slot in a vertical position and then in a horizontal position. When each slot 10 is in vertical position and its upper end is directed upwardly, it receives a tablet from a chute 12. The wheel then rotates ninety degrees to position the slot and the tablet horizontally, the wheels for each pair positioning the two tablets carried thereby end to end in alignment with one of the trays. A plunger blade 14 then advances to push

the two tablets out of the slots and into the tray. This operation is repeated at each station until each tray is filled with twelve tablets, each two tablets entering the tray after the first two are inserted pushing the others toward the other end of the tray. A cover plate extends over the trays as they pass from one station to another, the cover plate assisting in guiding the tablets in proper position into the trays.

10 Heretofore considerable difficulty has been experienced when for any reason the described feeding devices fail to properly feed the tablets into the trays. In accordance with the present invention, a cover plate 16 for the trays is provided which is hingedly mounted so as to enable it to be easily and quickly swung upwardly away from the trays so the feeding of the tablets into the trays may be conveniently observed, and in case the feed has been blocked to remedy the condition and in case any are missing insert additional tablets into the trays. The cover plate may then be easily swung down into its normal position and locked in position until again released by the operator and swung upwardly for inspection of the trays.

As shown, this cover plate is hinged at its outer edge by means of pivot studs 18 which are received in apertures in bearing blocks 20 on the machine frame. The cover plate is locked in its normal position by means of bolts 22 which are mounted to slide in bearing blocks 24. When the bolts 22 are projected, the reduced ends 26 thereof are received in locking recesses or apertures in fixed members 28 on the machine frame.

35 The bolts are adapted to be projected and retracted to lock and unlock the cover plate, by means of rocker arms 30 which are received in slots 32 in the blocks 24 and are secured on rock shafts 34 mounted in said blocks. The movements of the rock shafts 34 to project and retract the bolts 26 are limited by stop pins 36 on the hubs of the arms 30 engaging the end walls of the slots 32. The inner ends of the rock shafts 34 have arms 38 secured thereto which have their outer ends connected by a rod 40.

40 With this construction, upon swinging the arms 38 by means of the rod 40 upwardly to the broken line position shown in Fig. 2, the bolts 26 may be retracted and the cover plate 16 may be swung upwardly by using the rod 40 as a handle. When the cover plate is in this position, all of the trays being filled and the slotted feed wheels 8 are exposed to view, so that the operator may quickly and conveniently observe whether the tablets are 45 being properly fed into the trays. It will be ap-

parent that this may be done and faulty feeding of the tablets remedied without stopping the machine. Upon swinging the cover downwardly into its normal position, the bolts 26 may be projected to lock the cover in position through their connection with the handle rod 40.

It will thus be apparent by means of my hinged cover and devices for projecting and retracting the lock bolts, the cover may be easily and quickly swung upwardly for the purpose described and may be returned to its normal position. There is shown mounted on the cover and movable therewith, retarding plates 42 which operate through slots 44 in the cover. These plates are secured to blocks 46 which are pivotally mounted on a cylindrical rod or shaft 48 having its ends mounted in apertures in the bolt-carrying blocks 24. The rod has spacing sleeves 50 thereon to hold the blocks 46 in place. These plates 42 bear by gravity on the tops of the tablets as they enter the trays so as to cause the tablets to slide uniformly in proper end to end relation into the trays.

As will be evident to those skilled in the art, my invention permits various modifications without departing from the spirit thereof or the scope of the appended claims.

What I claim is:

1. In a box-filling machine of the class described, a plurality of trays arranged side by side and adapted to be fed sidewise in one direction intermittently, devices for feeding articles into a plurality of the trays through one of the ends thereof during the periods of rest of the trays, a cover plate beneath which the trays pass as they are moved into position to receive articles from said devices, a hinged connection between the outer edge of the cover plate and the machine frame whereby the cover plate may be swung upwardly to permit access to the tops of the trays, and means for locking the cover plate when it is swung down into position over the trays.

2. In a box filling machine of the class described, a plurality of trays arranged side by side and adapted to be fed sidewise in one direction intermittently, devices for feeding articles into a plurality of the trays through one of the ends thereof during the periods of rest of the trays, a cover plate beneath which the trays pass as they are moved into position to receive articles from said devices, a hinged connection between the outer edge of the cover plate and the machine frame whereby the cover plate may be swung upwardly to permit access to the tops of the trays, bolts mounted adjacent the ends of the cover plate to slide transversely thereof, sockets for receiving the ends of the bolts to lock the cover plate in position over the trays, rocker arms operatively engaging the bolts, shafts on which the rocker arms are secured, arms having one end secured to said shafts, and a handle rod connecting the other ends of said arms whereby upon swinging said arms in opposite directions said bolts may be projected and retracted and when the bolts are retracted the cover plate may be swung upwardly from the trays by means of said handle rod.

JOHN BOUSQUET.
